(57) **CLAIM**

The ornamental design for a cooler, as shown and described.

DESCRIPTION

FIG. 1 is a perspective view of a cooler;
FIG. 2 is a front side elevational view, the rear side elevational view being the mirror image thereof;
FIG. 3 is a top plan view thereof;
FIG. 4 is a bottom plan view thereof; and,
FIG. 5 is a left side elevational view, the right side elevational view being a mirror image of the present invention.
The broken lines are for illustrative purposes only and form no part of the claimed design.
